UNITED STATES PATENT OFFICE.

KORNAKICHI HORIKAWA, OF SEATTLE, WASHINGTON.

SASH-FASTENER.

1,239,105.

Specification of Letters Patent. Patented Sept. 4, 1917.

Application filed March 17, 1917. Serial No. 155,923.

To all whom it may concern:

Be it known that I, KORNAKICHI HORIKAWA, a subject of the Emperor of Japan, residing at Seattle, in the county of King 5 and State of Washington, have invented a new and useful Improvement in Sash-Fasteners, of which the following is a specification.

This invention relates to improvements in 10 window sash fasteners and the object of this improvement is to provide a relatively cheap and simple sash fastener of strong and durable construction that is neat in appearance and easy to install on any ordinary 15 window.

A further object is to provide a sash fastener that may be quickly and easily operated to lock the two sashes of a window and prevent movement thereof either when 20 they are closed or in any open or partially open position.

Still further objects are to provide a fastener that requires only one screw to rigidly secure it to the window sash and one 25 wherein the screw member will lie close to the window sash and be covered by a portion of the sash fastener frame.

The invention consists in the novel construction, adaptation and combination of 30 parts as will be more clearly hereinafter described and claimed.

In the accompanying drawings Figure 1 is a fragmentary view in perspective of a 35 double sash window upon which my fastener is installed and Fig. 2 is a view in perspective of the sash fastener apart from the window.

Referring to the drawings throughout which like reference numerals indicate like 40 parts the numeral 5 indicates a window frame and 6 and 7 are upper and lower window sashes respectively of well known form that are adapted to slide vertically between suitable stops 8 in the window 45 frame.

This fastener comprises a one piece frame or supporting member that is made up of a longer leg 9, a top portion 10 and a shorter leg 11 and presents somewhat the 50 appearance of an inverted letter L when viewed in side elevation.

The longer leg 9 is provided with a countersunk screw hole 12 and the shorter leg 11 terminates in an integrally formed 55 barb 13.

14 is a screw threaded spindle having a

thumb engaging element 15 on one end and a pivotally mounted washer or sash engaging plate 16 on the other end.

The spindle 14 passes loosely through a 60 suitable hole in the longer leg member 9 and is screwed through a similar hole in the shorter leg member 11 so that it lies closely beneath the top plate 10 and close to the top of the sash 7 and does not occupy much 65 room.

The fastener may be quickly and easily secured on a window sash by driving the barb 13 into the top of the sash and then inserting a screw 17 as shown in Fig. 1. 70

The two sashes are locked in any desired open or closed position by screwing the washer 16 tightly against the sash 6 thus causing the two sashes to securely bind 75 against the stops 8 and be locked against any force tending to open or close them.

The device thus provides an easy and simple means of securing a desired amount of ventilation and at the same time prevents burglars and the like from opening the window 80 from the outside sufficiently to gain admission to the house.

This device is also particularly useful in preventing window sash that are loose in the window frame from rattling when the 85 wind blows.

I am aware that window fasteners of a similar nature to mine have previously been made but so far as I know none of these have attained the simple construction, neat 90 appearance, ease of installation and strength of the present device.

This fastener is made up of three pieces namely the frame member the threaded spindle and the sash engaging washer and can 95 be rigidly secured to the window sash by a single screw. Moreover it will be noted that the spindle 14 lies very close to the top of the sash 7 so that the thrust applied through the screw has very little tendency 100 to pry the fastener frame off of the sash and that the thrust is practically all sustained by the barb member 13.

The frame member is easily formed by simple stamping and bending operations. 105

Obviously changes in the precise form of construction of the various parts of the device may be resorted to within the scope of the appended claim.

What I claim and desire to protect by 110 Letters Patent is:

The combination with a window having

an upper and a lower sash of a sash fastener comprising an integral L-shaped frame said frame having a longer leg adapted to extend downwardly over the side of said lower sash, a shorter leg adapted to rest upon the top of said lower sash and a top portion connecting said two legs, a barb on said shorter leg portion to project into the top of said sash, a screw threaded spindle 10 extending through said leg portions and disposed between the top of said lower sash

and the top portion of said frame and a washer swiveled on the outer end of said spindle to engage with said upper sash and frictionally lock said two sashes. 15

Signed by me at Seattle, Washington, this 10 day of March, 1917.

KORNAKICHI HORIKAWA.
